UNITED STATES PATENT OFFICE.

ALFRED CARLSON AND JOHN W. CARLSON, OF LAGRANDE, OREGON.

GOLD-AMALGAMATOR.

SPECIFICATION forming part of Letters Patent No. 534,196, dated February 12, 1895.

Application filed August 6, 1894. Serial No. 519,598. (No model.)

To all whom it may concern:

Be it known that we, ALFRED CARLSON and JOHN W. CARLSON, citizens of the United States, residing at Lagrange, in the county of Union and State of Oregon, have invented a new and useful Gold-Amalgamator, of which the following is a specification.

This invention relates to gold amalgamators; and it has for its object to effect certain improvements in machines of this character wherein simple and efficient means shall be provided for separating fine flour gold from sand, and collecting or recovering such gold.

15 To this end the main and primary object of the present invention is to provide a gold amalgamator machine that shall insure the separation and collection of fine flour gold from sand, much of such gold being lost or wasted in the ordinary separating processes.

With these and other objects in view which will readily appear as the nature of the invention is better understood, the same consists in the novel construction, combination 25 and arrangement of parts hereinafter more fully described, illustrated and claimed.

In the drawings:—Figure 1 is a perspective view of a gold amalgamator machine constructed in accordance with this invention. 30 Fig. 2 is a central vertical longitudinal sectional view of the same. Fig. 3 is a cross section on the line $x-x$ of Fig. 2. Fig. 4 is a detail in perspective of the revolving agitator or mixer.

35 Referring to the accompanying drawings, 1 designates a cylindrical receiver that is constructed of any suitable material adapted for the purposes of the machine and in any suitable size according to the capacity of the machine to be made. The receiver 1, is preferably cylindrical and is provided with an upper open end that is adapted to removably receive the circular attaching neck or flange 2, projected from the under side of the upwardly flared hopper 3. The upwardly flared hopper 3, is inclosed at the sides and end and is open at the top, and said upwardly flared hopper 3, has projected upwardly from the opposite ends thereof the opposite connected 45 end plates 4, provided with the aligned bearing openings 5, in which are journaled the

opposite extremities of the inclined drum shaft 6, on which is mounted the rotary screen drum 7. By reason of the inclined disposition of the shaft 5, the screen drum 7, is necessarily given an inclination so as to decline from one end plate to the other, between which plates the said drum is arranged to rotate, and the drum essentially comprises the opposite spider frames 8, and a wire screen 60 or perforate metal periphery 9, fitted onto the spider frames 8. The inclined rotary screen drum 7, is open at both ends and is adapted to receive at the higher open end thereof the earthy material, sand, and water 65 containing the gold to be collected, through the inlet opening 10, formed in one of the end plates 4, and fitted into the inlet opening 10, is the lower end of the inclined trough 11, into which the water and gold bearing substances are introduced for the purpose of separating the gold from the substances carrying the same and then collecting the gold. A rotation is imparted to the drum 7, by means of the belt 12, embracing an end pulley portion 13, of said screen drum, said belt being also passed around suitably arranged idler guide pulleys 14, mounted within the hopper 3, and driven from the wheel or pulley 15 mounted on the transverse drive shaft 16, 70 journaled transversely of the hopper 3, in opposite sides thereof and being adapted to be driven by any suitable gearing connections therewith.

The materials that pass into the rotary 85 screen drum 7, are subjected to a thorough separating action, and the larger gravel, rocks, earth, &c., pass out of the lower open end of the screen drum and discharge through the discharge opening 17, formed in one of the end plates 4, and are directed off from the machine by the inclined tailings chute 18, secured to one end of the hopper 3. It will be understood, as illustrated in the drawings, that the pulleys and other gearing arranged within the hopper 3, are preferably inclosed at the exposed portions thereof by the shield caps or covers 19, that keep out the sand and dirt from the gears and prevent them from clogging, and the open top of the 90 hopper and the rotary screen therein are inclosed by the removable circular casing top 95 100

20, provided at opposite ends with the flanges 21, that engage over the opposite end plates 4, to provide for removably securing the top in position while at the same time admitting 5 of the ready removal thereof for the purpose of gaining access to the screen or other working parts of the machine.

The fine sand and water pass through the screen after being relieved from the larger 10 gravel, rocks, earth, &c., and pass out of the bottom of the hopper into the vertical discharge spout or tube 22, that projects from the bottom opening of the hopper and depends within the cylindrical receiver 1, to a point above the closed bottom of such receiver. The said discharge spout or tube 22, carries the fine sand and water directly to the bottom of the receiver 1, into the mercury or quick silver 23, that is adapted to be placed 15 within the bottom of the receiver 1, on the removable bottom copper collecting plate 24, that is removably fitted into the bottom of the receiver 1, to provide for collecting the gold from the fine sand and water as it is 20 agitated around in the mercury or quick silver bath 23, and the materials that pass down through the discharge spout or tube 22, are caused to pass directly into the bath of mercury or quick silver, by reason of the adjustable end ring 25. The adjustable end ring 25, is fitted snugly over the lower end of the discharge spout or tube 22, and is adapted to be adjusted to bring its lower edge down to the surface of the loose mercury or quick 25 silver 23, and the adjustment of the ring is rendered necessary according to the quantity of mercury or quick silver, and when properly adjusting the parts of the machine together for operation.

40 The fine sand and water when it reaches the bath of mercury or quick silver in the bottom of the receiver 1, are thoroughly agitated or mixed into the same by means of the rapidly revolving agitator 26. The rapidly 45 revolving agitator 26, works in the bottom of the receiver 1 directly below the adjustable end ring 25, and comprises a radial series of horizontal twisted blades 27, and upturned paddle projections 28, bent upwardly from 50 each of the blades at their inner ends, and said agitator or mixer is adjustably mounted on the lower threaded ends 29 of the vertical agitator shaft 30, the adjustment of said agitator or mixer providing means for properly 55 adjusting the same relative to the end ring 25, as adjusted.

Relative to the specific construction of the agitator 26, it is to be noted that the horizontal twisted blades 27 have their lower 60 edges carried in a forward direction as the agitator revolves, thereby providing not only for a thorough agitation of the water and sand within the bottom of the receiver, but at the same time, have a tendency to accelerate 65 the circulation of water and sand upwardly, and out through the discharge or

overflow openings 35 formed in opposite sides of the receiver, and the upturned paddle projections 28 at the inner ends of the blades 27 serve to provide for the proper agitation of the water and sand at the center of the agitator, or directly adjacent to the shaft 30, where the twist of the blades 27 is the least. The shaft 30, is stepped at its lower end in the bearing step 31, formed centrally on the bottom amalgamating collecting plate 24, and is journaled at its upper end in the bearing bar 32, arranged within the hopper 3. The shaft 30, has mounted on the upper extremity thereof the horizontal beveled gear wheel 33, that meshes with the vertical beveled gear wheel 34, mounted on the shaft 16, which is speeded so as to rotate the agitator or mixer at quite a high rate of speed. The water and fine sand after being subjected to agitation 85 within the bottom of the receiver is worked out through the side discharge or overflow openings 35, formed in opposite sides of the receiver, and in being worked out through said openings, the sand and water are brought 90 in contact with the upper and lower amalgamated side collecting rings 36 and 37 respectively. The rings 36 and 37, are made of amalgamated copper to provide for the collection of any gold that is brought into contact therewith and the same are fitted one within the other in the lower end of the receiver 1, directly above the bottom collecting plate 24. The lower of said rings, 37, is stationary, and the upper ring 36, is adapted to have a sliding 100 adjustment within the lower ring, so as to cover and uncover the lower portion of the side openings 35, in order to regulate the rapidity of overflow or discharge through the said openings. The said upper ring 36, is also provided upon its inner side with the annular parallel baffle flanges 38, that cause the materials to be retarded in their passage out of the receiver, and thereby insures the more thorough collection of the flour gold. 110

After passing out through the side discharge openings 35, the materials pass into the opposite curved side inclined discharge troughs 39, that lead into a common discharge neck 40, and said opposite side inclined discharge 115 troughs and the common neck 40, thereof are separated into the gold collecting pockets 41, by the curved partition plate or flange 41^a, fitted within the neck 40, at the point where the troughs 39, lead thereinto, and removably 120 fitted in the bottom of the several pockets 41, are correspondingly shaped removable amalgamating plates 43, that provide for the collection of any gold that may have escaped amalgamation in the other parts of the machine. 125

All of the amalgamated plates and rings of the machine are removable so as to provide for recovering the gold collected thereby and for the replacement of the same, and the free mercury or quicksilver contained in the bottom 130 of the receiver 1, may be drawn out when de-

sired through the cock or faucet 44, fitted into the rear side of the receiver in connecting with the bottom thereof.

The operation and many advantages of the herein-described gold amalgamator will be readily apparent to those skilled in the art, and it will be understood, that changes in the form, proportion and the minor details of construction may be resorted to without departing from the principle or sacrificing any of the advantages of this invention.

Having thus described the invention, what is claimed, and desired to be secured by Letters Patent, is—

1. In an amalgamator, an upright receiver provided with side discharge openings above the plane of its bottom and adapted to hold a bath of mercury below said side discharge openings, a side collecting ring adjustably fitted within the receiver above the bottom thereof and adapted to cover and uncover the lower portion of said side discharge openings, and a vertically adjustable revolving agitator or mixer mounted to rotate within the bottom portion of the receiver below the plane of the side discharge openings thereof, substantially as set forth.

2. In an amalgamator, the combination of an upright receiver having amalgamating devices in its lower end, a removable downwardly flared hopper provided with a circular attaching neck or flange adapted to removably fit inside of the upper end of said receiver, opposite connected end plates arising from opposite ends of the hopper and provided with inlet and discharge openings respectively, an inclined screen drum mounted to rotate between the connected end plates and having its open ends communicating with said inlet and discharge openings, a circular casing top 20 having end flanges 21 removably fitted over the opposite end plates an inclined trough fitted into the inlet opening of one end plate, and an inclined tailings chute disposed below projected from the discharge opening of the other end plate, substantially as set forth.

3. In an amalgamator, the combination of an upright receiver provided with side discharge openings disposed above the bottom thereof, a removable hopper having a depending discharge spout or tube adapted to project into the receiver below the discharge openings thereof, a revolving agitator or mixer mounted to revolve within the bottom of the receiver below said discharge spout or tube, an inclined rotary screen mounted to rotate within the hopper, and gearing devices mounted within the hopper and connected 60 with the rotary screen drum and said revolving agitator or mixer, substantially as set forth.

4. In an amalgamator, an upright receiver provided with side discharge openings above the plane of its bottom, a removable hopper

fitted to the receiver and provided with a depending discharge spout or tube projecting thereinto, an end ring 25 adjustably fitted onto the lower end of said discharge spout or tube for vertical adjustment to the surface of the mercury contained in the bottom of the receiver, a vertical agitator shaft arranged within said discharge spout or tube, a vertically adjustable revolving agitator mounted on the lower end of said shaft below said adjustable end ring, and adapted to be adjusted relatively to said end ring and a separating device arranged above the hopper, substantially as set forth.

5. In an amalgamator, an upright receiver provided with side discharge openings above the plane of its bottom, an amalgamated collecting plate removably fitted on the bottom of the receiver, side collecting rings removably fitted within the receiver above the bottom collecting plate, one of said rings being adjustable to cover and uncover the lower portion of said side discharge openings, a hopper removably fitted to the upper end of the receiver and provided with a depending discharge spout or tube, a separating device arranged above the hopper, and a revolving agitator mounted to work within the bottom of the receiver below said depending discharge spout or tube, substantially as set forth.

6. In an amalgamator, the combination of an upright receiver provided with side discharge openings above the plane of its bottom, an amalgamated collecting plate removably fitted on the bottom of the receiver, amalgamated collecting rings removably fitted inside of the receiver above the bottom plate, the upper of said rings having a sliding adjustment to cover and uncover the lower portion of said side discharge openings and provided upon its inner side with annular parallel baffle flanges, a hopper removably fitted to the upper-end of the receiver and provided with a depending discharge spout or tube, a separating device arranged above the hopper, a revolving agitator working within the bottom of the receiver below said spout or tube, and opposite curved discharge troughs secured at an angle to opposite sides of the receiver below the side discharge openings thereof, substantially as set forth.

7. In an amalgamator, the combination of an upright receiver provided with side discharge openings above the plane of its bottom, the amalgamating devices arranged within the receiver, opposite curved discharge troughs secured at an angle to opposite sides of the receiver below its discharge opening, said troughs being contracted into a common discharge neck and provided with separated gold collecting pockets, and amalgamated collecting plates removably fitted in said pockets, substantially as set forth.

8. In an amalgamator, the combination with

the receiver, the hopper, and a vertical shaft; of a revolving agitator or mixer comprising a radial series of horizontal twisted blades having integral upturned paddle projections at their inner ends directly adjacent to said shaft, substantially as set forth.

5 In testimony that we claim the foregoing as

our own we have hereto affixed our signatures in the presence of two witnesses.
